UNITED STATES PATENT OFFICE.

SUGDEN SHACKLETON, OF KEIGHLEY, ENGLAND, ASSIGNOR TO THE FIRM OF PRINCE SMITH & SON, OF KEIGHLEY, ENGLAND.

COMBING MACHINERY.

SPECIFICATION forming part of Letters Patent No. 790,757, dated May 23, 1905.

Application filed November 4, 1904. Serial No. 231,412.

To all whom it may concern:

Be it known that I, SUGDEN SHACKLETON, draftsman, a subject of the King of Great Britain, residing at 26 Mannville road, Keighley, in the county of York, England, have invented certain new and useful Improvements in or Relating to "Nobles" or Like Combing Machinery, of which the following is a specification.

10 My present invention relates to improvements in or relating to the Nobles or like combing machinery, and has for its principal objects to attain an improved method of mounting the pillars carrying the vertical and the 15 horizontal driving-shafts. Heretofore it has been customary to carry these on a rail or cross-bar running across the center of the large steam-chest. The unequal contraction, when cooling, in casting these steam-chests has 20 been a source of great trouble, and a large percentage of these have to be thrown away in consequence of this defect, and, moreover, these cross-bars or "S-rails," as they are sometimes called, tend to "crowd" or fill up valuable 25 space in the comb in the center where the sliver-funnels and the drawing-off rollers are situated, and the construction sought to be dispensed with has other material defects. I also attain by my improved construction a 30 simpler and easy method of dismantling the top part of the comb without disturbing the mechanism on the bottom part of same when changes or repairs are desired.

In the drawings, Figure 1 is a front elevation, partly in section, of a combing-machine with my improvements applied thereto. Fig. 2 shows a portion of a combing-machine to a larger scale than the preceding figure, showing more clearly my improvements, the left-hand half being mainly in section and the right-hand half in elevation. Fig. 3 is a plan view of the gearing. Fig. 4 is a similar view to Fig. 1, but showing the top part of the comb separated or dismantled with a lifting-hook attached.

a a indicate a pair of base-columns. *b* is a gearing-plate. *c* is a cavity at the top of each base-column. (Here shown only in the sectional views of the columns in Figs. 1 and 2.)

d is the annular wheel, mounted on the shaft 50 *e*. *f f* are the pillars. *g* is the upper driving-shaft. *h* is the small steam-chest. *i* is a flange on pillar *f*. *j* is a pinion intermeshing with wheel *d*. *k* represents the base-column flanges. *l l* are nuts and bolts connecting 55 flanges *i* and *k*. *m* is the lower flange of each base-column *a*. *n n* are bolts and nuts connecting flange *m* to plate *b*. *o* is an annular flange to carry steam-chest *h*. *p* is the larger steam-chest, and *s* is a lifting-hook for removing the top part of the comb.

In carrying out my invention I am enabled to do away entirely with the cross-bar or S-rail before alluded to and to carry the pillars *f f* upon base-columns *a a*, which columns 65 are rigidly affixed by flanges *m* and bolts *n* to a gearing-plate *b*. In the top of each base-column *a* is a chamber, recess, or cavity *c*, within which is placed or fitted an annular wheel *d*, said annular wheel being fixed to the upper end 70 of the lower portion of the vertical driving-shaft *e*. The upper portion *g* of the vertical driving-shaft carries at its lower end a spur pinion-wheel *j*, and this wheel *j* is geared into the annular wheel *d* already mentioned, as shown 75 more clearly by Fig. 3. Thus rotation imparted to the one causes both wheels to run in the same direction. As will be seen, the pillar *f* carries the upper portion *g* of the vertical driving-shaft. Each base-column *a* is flanged on 80 its upper part *k*, while each of the pillars *f* is flanged on its bottom part *i*. These flanges of the pillar *f* and of the base-column *a*, respectively, are held together by means of screws or like fastenings *l*, the whole forming 85 an efficient and effective cover for the before-described gears and making a rigid support for the vertical driving-shafts *g* and *e*. A suitable flange or ring *o* is cast on the base-column *a*. Fig. 4 shows the same parts as are 90 delineated in Fig. 1, but with the top portion of the comb separated or dismantled by means of a lifting-hook attached thereto. To this hook may be fitted ordinary pulley-blocks (not shown) for raising, lowering, and removing 95 the top portion of the comb.

Having now particularly described and ascertained the nature of my said invention and

in what manner the same is to be performed, I declare that what I claim is—

1. In a circle comb of the class set forth, a base-column, a gearing-plate supporting said column, the column having a cavity formed in its upper extremity, a driving-shaft extending upwardly through the column having an internally-toothed gear-wheel in the cavity, in combination with a pillar separably held on the column, a shaft mounted in said pillar and carrying a pinion at its lower extremity meshing with the internally-toothed gear, and a small steam-chest carried by said pillar. 30
2. In a circle-comb of the class set forth, a pair of base-columns, a pair of flanged pillars separably seated on the said columns, driving-shafts extending through the columns and pillars and having intermeshing gearing means in concentric relation within the joined portions of the columns and pillars, and operating accessories. 35
3. In a circle comb of the class set forth, a base-column, a gearing-plate affixed thereto, the upper part of the column having a cavity therein, an internally-toothed wheel located in said cavity, a pillar, a pillar-base, the pillar being separably connected to the column, 40

shafts located in the column and pillar, one of which is connected to the toothed wheel, and the other having a pinion meshing with the latter, and operating accessories for the said parts. 45

4. In a circle comb of the class set forth, a pair of base-columns, a pair of pillars separably connected to the columns, driving-shafts extending through the pillars and columns and having intermeshing gearing at the point of jointure of the latter, and small annular steam-chests coöperating with the columns. 50

5. In a circle comb of the class set forth, a pair of base-columns, a pair of pillars separably connected to the columns, driving-shafts extending through the pillars and columns and having intermeshing gearing at the point of jointure of the latter, small annular steam-chests coöperating with the columns, and a larger steam-chest arranged as set forth. 55

In testimony whereof I have hereunto set my hand in presence of two subscribing witnesses.

SUGDEN SHACKLETON.

Witnesses:

HENRY SMITH,
THOMAS HOLMES SOUTHWELL.
